UNITED STATES PATENT OFFICE

ERNEST EDWARD PALMER, OF TORONTO, ONTARIO, CANADA, ASSIGNOR TO THE CLEVELAND FOLDING MACHINE COMPANY, OF CLEVELAND, OHIO, A CORPORATION OF OHIO

PAPER OR LIKE SHEET-FOLDING MACHINE

Application filed September 10, 1927, Serial No. 218,762, and in Great Britain September 13, 1926.

This invention relates to paper or like sheet folding machines and is applicable to machines operating on either the buckling or knife folding principle or embodying both principles and has for its object to reduce the manufacturing and maintenance costs of such machines and simplify their working without in any way impairing their efficiency.

In some types of folding machine the arrangement of the mechanism is such as to enable parallel and transverse folds to be made in a sheet in a variable sequence and number so that when required certain of the folding sets may be cut out of action while others are operative.

Now where only a limited number of folds is to be made and it is undesirable for the sheets to be carried right through the machine to the collector box it has been customary hitherto to arrange individual collecting boxes for the delivery of the signatures at different parts of the machines, thereby adding to the costs of manufacture and maintenance. The object of the invention is to avoid this and to enable the folded sheets to be delivered from any part of the machine to a common receiving or delivery device in a simple and inexpensive manner.

To this end according to the present invention use is made in a folding machine having more than two folding sets of a delivery device, such as a stacker, adapted to receive signatures from one or other of two or more of said folding sets and, advantageously, from any one thereof. This is preferably effected by means of chutes or deflecting guides employed for guiding the signatures from the selected folding set to the delivery device proper.

To enable signatures emerging from a folding set to be directed selectively either to the delivery device or to a folding set or to one of a number of different folding sets said chutes or deflecting guides may as usual be constructed so as to act as switches by, for example being made rotatable, oscillable or removable. Thereby the signatures may be caused or allowed selectively to pass either to a further folding set or sets or to the delivery device.

In constructions of folding machines appropriate to the general principle of a delivery common to several folding sets it may be desirable for a sheet carrying device such as a cross-carrier, to be disposed below the common delivery device or stacker. The signatures must then be conveyed upwardly in order to reach said delivery. This upward conveyance may advantageously be performed during their passage through a folding set or immediately before or after the same.

The advantages of a common delivery arrangement are enhanced by the use, where necessary, of deflectors for cutting out individual folding sets not required for any particular run. These deflectors may be of the known type which is substituted for the folding plate as a whole or of the type pivotally secured to a retractable plate.

Various embodiments of the invention are illustrated by way of example in the accompanying drawings in which:

Figs. 1-6 illustrate a machine employing buckling folding sets and having a common delivery apron travelling at right angles to the direction of feed on the feed table.

Fig. 1 being a side elevation thereof.

Fig. 2 an end elevation.

Fig. 3 a plan, partly in section on the line A—A in Fig. 1.

Fig. 4 a detail sectional view of the parallel folding sets, the view being taken substantially on line B—B Fig. 2.

Fig. 5 a detail sectional view of the first cross folding set and

Fig. 6 a detail sectional view of the second cross folding set.

Figs. 7-9 illustrate a modified form of the folding machine shown in Figs. 1-6 wherein the delivery apron lies longitudinally parallel to the feed table.

Fig. 7 being a side elevation thereof,

Fig. 8 an end elevation and

Fig. 9 a detail sectional view of the parallel folding sets, the section being taken substantially on line C—C of Fig. 8.

Figs. 10-14 illustrate the application of the invention to a machine incorporating

folding sets of both the buckling and knife type.

Fig. 10 being a side elevation thereof partially in section.

Fig. 11 an end elevation also partially in section.

Fig. 12 a detail sectional view illustrating delivery from a folding set producing a fold parallel to the first cross fold and

10 Figs. 13 and 14 similar views illustrating alternative manners of delivering direct from the first cross folding set.

Fig. 15 is a detail sectional view illustrating the use of deflectors for cutting out individual components from a bank of folding sets.

20 Figs. 1-6 of the accompanying drawings illustrate the invention as applied to a folding machine of the buckling type wherein the common delivery apron or stacker 1 moves perpendicularly to the line of entry of the sheets on the feed table 2. Said feed table supplies sheets to the rolls 3, 4 of the parallel folding sets which comprise three folding plates 5, 6, 7 and folding rolls 8, 9, 10 in addition to the rolls 3, 4. In these parallel folding sets the sheet may be given from one to three parallel folds, folding plates not required being replaced by deflectors in the well known manner (Fig. 15). From the last pair of rolls 9, 10 of the parallel folding sets the sheet may be delivered either direct to the conveyor or to a first cross-carrier 11 which is of the type employing oblique rolls 12. 30 35 For this purpose beyond said rolls 9, 10 an adjustable unit is provided comprising a deflector or guide 13 and a pair of shafts carrying scoring discs and/or feed rolls 14, 15. In Fig. 4 this unit is shown in full lines in the position in which it is secured when sheets are to be delivered to the cross-carrier 11 and in dotted lines in its position for passing the sheets direct to the stacker 1.

40 45 In the former case the cross-carrier 11 conveys the sheets to the first cross-folding set consisting of the fold plate 16 and rolls 17, 18, 19. The sheets may be delivered from this set either direct to the stacker or to a second cross-carrier 20. To this end provision is made once more of an adjustable unit which comprises a deflector in two parts 21, 22 and shafts carrying scoring discs and/or feed rolls 23, 24 all carried on laterally disposed arms 25 pivoted at 26 to brackets 50 55 27 on the machine frame. (Fig. 5.) These lateral arms 25 may be secured by plungers passed through holes in said arms into one of the holes 28, 29, in each of said brackets. In Fig. 5 the unit is shown in position for 60 65 delivering to the stacker 1. When lowered to deliver to the cross-carrier 20 the lower part 22 of the deflector combines with a fixed guide 30 to provide a continuous guide-way on to said cross-carrier. The shafts carrying the scorers or feed rolls 23, 24 are driven from

the roll 19 through a gear 31 which naturally must be adjustable in order to enable it to roll on the corresponding gear on the roll 19 when the unit is swung about 26. For this purpose the shaft of the gear 31 is journaled in slots 32 in the arms 25.

70 If delivered to the second cross-carrier 20 the sheets are passed thereby to a second cross folding set consisting of rolls 33, 34 and 35 and folding plate 36. This set is so disposed as to deliver on to the stacker and, since the latter is situated above the carrier 20, a novel arrangement of the rolls and plate is necessary. From the cross-carrier 20 the sheets pass up between feed rolls 37, 38 over a guide 39 into the rolls 33, 34 of the folding set. On emerging from the plate 36 the sheets pass between the rolls 34, 35 and are delivered over or through a guide 40 on to the stacker 80 assisted by feed rolls 41, 42 if necessary.

85 The arrangement illustrated in Figs. 7, 8, and 9 differs from that above described merely in that the stacker 1, consisting of a continuous conveyor apron is disposed in the machine parallel to the feed table 2.

90 The parallel folding sets are constituted and arranged in the same way as in the previous case but the extension of the stacker underneath the feed table 2 provides a further alternative for delivering from the parallel sets. For this purpose the fold plate 7 is so constructed that if delivery is required after one transverse fold has been made said plate can be converted into a "through" plate by removing therefrom the usual stops 7'. It will then merely constitute a guide for the sheets which will emerge from the plate on to the stacker 1 (Fig. 9).

95 100 105 The parallel position of the stacker also allows of an alternative construction for the switching means following the parallel folding sets. In the present example said switching means comprise two pairs of non-adjustable shafts, one pair carrying scoring discs and/or feed rolls 14' 15', and the other feed rolls 14" 15", and a removable deflector 40. If the sheets provided with the desired number of parallel folds are to be delivered to the cross-carrier 11 the deflector 40 is set in the position shown with dotted lines in Fig. 9 so that on emerging from the rolls 9, 10 the sheets are guided by the deflector 40 between the scoring discs or feed rolls 14' 15' on to the cross-carrier. If on the other hand the sheets are to be discharged direct on to the stacker the deflector 40 is removed and the sheets then pass downwardly between the rolls 14" 15" and over the guide 41 on to the stacker 1. Naturally the removable deflector 40 might be replaced by a pivotal two position deflector.

110 115 120 125 As in the previous example the cross-feeder delivers the sheet to the cross folding set 16, 17, 18, 19 whence, depending on the position of a delivery unit similar to that de-

scribed above, it may be passed to the second cross-carrier 20 or discharged direct to the stacker 1. The second cross-feeder conducts the sheets to the second cross folding set 33, 34, 35, 36 in passing through which the sheets are elevated to the level of the stacker 1.

It will be appreciated that the fold plate of any folding set which in any particular run is not to be operative to produce a fold 10 may be replaced for that run by a deflector plate so arranged that the sheet proceeds unfolded in precisely the same direction as it would had said plate been in action.

Figs. 10-15 illustrate the application of the 15 present invention to a folding machine of the type combining buckling and knife folding sets. It will be seen that sheets delivered from a feed board or table 2 pass through parallel folding sets precisely similar to those 20 already described. As in the example illustrated in Figs. 7-9 the stacker 1 is disposed parallel to the feed table so that it is possible, in this instance also, to adapt the fold plate 7 for use, when desired, as a through plate or 25 guide delivering direct on to the stacker apron 1. Feed rolls 42 may be associated with said plate 7 in the manner set forth for example in specification of British Patent No. 234,126 so that when the plate is to be used as a guide 30 said rolls can be adjusted to assist the travel of the sheet therethrough. This arrangement is of particular advantage in the present example because the stacker is rather far below the parallel folding sets but it is 35 also applicable to the buckling folding machine previously described.

If the sheets are to receive one or more cross folds before stacking they pass from the parallel folding sets on to the table 43 and fetch 40 up against the usual stops for folding by the knife 44 and the rolls 45 and 46. After receiving this fold the sheets may either be folded at right angles or parallel to the same or may be delivered direct to the stacker 1.

If a cross fold is to be imparted (Fig. 11) 45 the sheets are merely allowed to pass vertically downwards from the rolls 45 and 46 on to a pivoted deflector surface 47 which directs them on to a table 48 for folding by the knife 49 and rolls 50 and 51. The latter discharge 50 the sheets over a guide 52 on to the stacker 1.

When a parallel fold is desired the sheet is directed towards the buckling folding set 53, 54, 55, 56 by a pivoted deflector 57 which can be swung from an inoperative position (Figs. 55 11 and 13) to that shown in Fig. 12 in which it co-operates with the fixed guide 58. Delivered from this folding set by the rolls 54, 55 the sheet is guided by the removable deflector plate 58' on to the stacker 1. To enable 60 said plate 58' to be correctly positioned, the pivoted deflector 47 must be swung to the position illustrated in Fig. 12.

For delivering direct from the rolls 45, 65 46, to the stacker 1 the arrangement is the

same as that shown in Fig. 12 except that the pivotal deflector 57 is swung out of position (Fig. 13). Alternatively, however, said deflector 57 may be left in its operative position and the buckling plate 56 replaced by a 70 deflector 60 (Fig. 14) whereby the same result is obtained.

The use of deflectors similar to 60 is applicable to any folding plate or plates which are not required for a run. Fig. 15 illustrates the 75 employment of deflectors 61, 62 in a bank of parallel folding sets.

The arrangements of the folding sets, cross-carriers, and delivery apron described above with reference to the drawings are naturally 80 to be regarded as examples only of the application of the invention to particular types of machine and it is obviously applicable also to types of machine having a larger or smaller number of fold plates and having 85 said fold plates, cross-carriers, delivery apron and other elements disposed in a manner other than that illustrated.

What I claim is:—

1. In a paper handling machine, a plurality 90 of sheet feeding conveyors adapted to handle consecutively sheets passing through the machine single file, means at the delivery end of each conveyor for performing an operation upon the sheets, a sheet delivery conveyor, and a movable deflecting guide in connection with each of said operating means for feeding sheets onto said delivery conveyor or without passing them over the succeeding sheet feeding conveyors. 95

2. In a paper handling machine embodying a plurality of mechanisms for operating consecutively upon sheets of paper or the like, a common sheet delivery conveyor, and means for feeding sheets from any one of 105 said mechanisms directly onto said conveyor.

3. In a paper handling machine, a plurality of means at separated points for performing operations upon sheets of paper or the like passing through said machine, and a sheet moving means adapted to receive sheets directly from any one of said first named means selectively. 110

4. In a paper handling machine, a plurality of means at separated points for performing operations upon sheets of paper or the like passing through said machine, and a stacker adapted to receive sheets directly from any one of said means selectively. 115

5. In a paper handling machine, folding means, two sheet moving tables arranged in superposed relation adapted to move the folded sheets in two different directions, a stacker, and means for feeding sheets from either of said tables onto said stacker. 120

6. In a paper handling machine, two sheet moving tables arranged in superposed relation, a stacker interposed between said two tables, and means at the delivery end of each table for operating upon said sheets, said 125

- operating means being adapted to deliver sheets onto said stacker.
7. In a paper handling machine, two superposed sheet moving tables, means at the delivery end of one of said tables for operating upon said sheets, a stacker, and means at the delivery end of the upper table for feeding sheets onto either the lower table or said stacker.
8. In a paper handling machine, two superposed sheet moving tables, a stacker, and means at the delivery end of the upper table for operating upon said sheets, said means being adapted to feed the sheets either onto the lower table or onto said stacker.
9. In a paper handling machine, two superposed sheet moving tables, means at the delivery end of one of said tables for operating upon said sheets, a stacker interposed between said two tables, and means at the delivery end of the upper table for feeding sheets either onto the lower table or onto said stacker.
10. In a paper handling machine, two superposed sheet moving tables, a stacker interposed between said two tables, and means at the delivery end of the upper table for operating upon said sheets, said means being adapted to feed the sheets either onto the lower table or onto said stacker.
11. In a paper handling machine, two superposed sheet moving tables, means at the delivery end of one of said tables for operating upon said sheets, a stacker means at the delivery end of the upper table for feeding sheets either onto the lower table or onto the said stacker, and means at the delivery end of the lower table for feeding sheets onto said stacker.
12. In a paper handling machine, two superposed sheet moving tables, means at the delivery end of one of said tables for operating upon said sheets, a stacker interposed between said two tables, means at the delivery end of the upper table for feeding sheets either onto the lower table or onto said stacker, and means at the delivery end of the lower table for feeding sheets onto said stacker.
13. In a paper handling machine, a plurality of sheet feeding conveyors adapted to handle consecutively sheets passing through the machine single file, means fixed upon the machine at the delivery end of each conveyor for performing an operation upon the sheets, a sheet delivery conveyor, and means adjustable at will to feed sheets onto said delivery conveyor following any one of said operations without passing them over the succeeding sheet feeding conveyors.
14. In testimony whereof I hereunto affix my signature this 29th day of August, 1927.
- ERNEST EDWARD PALMER.
